UNITED STATES PATENT OFFICE.

HOWARD F. WIERUM, OF UPPER MONTCLAIR, NEW JERSEY.

GAS-BURNER.

1,109,272.

Specification of Letters Patent.

Patented Sept. 1, 1914.

Application filed October 9, 1913. Serial No. 794,295.

To all whom it may concern:

Be it known that I, HOWARD F. WIERUM, a citizen of the United States, residing at Upper Montclair, in the county of Essex and 5 State of New Jersey, have invented certain new and useful Improvements in Gas-Burners, of which the following is a specification.

The object of the present invention is the production of a gas burner in which the 10 flame will be thoroughly controllable and in which the air and gas shall be very completely mixed before passing out of the burner structure, in order that the flame may be maintained either oxidizing or reducing, 15 irrespective of the quality of the atmosphere in the space in which the flame is burning. This burner is intended for use particularly in multiple shelf reverberatory ore roasting furnaces in which the atmosphere, 20 particularly in the upper compartments, is liable to be extremely bad, so that difficulty may be encountered in operating ordinary gas burners, and especially if the degree of oxidation or reduction of the flame must be 25 controlled.

In the accompanying drawings, Figure 1 illustrates partly in vertical section and partly in elevation a burner constructed in accordance with my invention. The cone in 30 said burner being shown as taken on the section line 1—1 of Fig. 2. Fig. 2 shows on a somewhat larger scale, an end view of the cone of the device shown in Fig. 1. Fig. 3 shows a modified structure of burner involving my invention, in which a different form of mixing member is used in place of the cone above referred to.

In said drawings 10 and 11 represent respectively gas and air supplies and are connected to suitable pipes provided with valves for the proper regulation of the respective amounts of gas and air. The pipe 10 is connected to the pipe 12 by means of the elbow 13, and the pipe 12 terminates within 45 the outer casing 14 at a point just back of the mixing cone 15, as shown in Figs. 1 and 2. After the gas leaves the pipe 12 it mixes with the air supplied by pipe 11, said mixing being greatly accelerated by means of the 50 gas and air passing through the non-radial perforations 16 in the cone shaped member. The passage of the gases through the slots 16, with considerable force, imparts a spiral motion to the gases in the chamber 17 located around the cone shaped member 15, which mixes the gas and air very com-

pletely. Since the mixture of gas and air in the chamber 17 is in the proper proportions for combustion it is explosive, and to prevent the flashing back of the flame into this chamber, a fine wire gauze 18 is located at or near the end of said chamber 17 as illustrated. The chamber 17 may be of somewhat larger diameter than the middle part 19 of the burner itself, as shown in Fig. 1, or it may be 60 the same size and may be integral therewith as shown in Fig. 3.

Referring now more particularly to that form illustrated in Fig. 3, I may provide a bushing 20 in the pipe formed of the two 70 portions 14^a and 19^a near the termination of the pipe 12, and may connect to this a cylindrical chamber 21 provided with a closed end 22, and also provided with non-radial helically arranged slots 23, which produce 75 substantially absolute mixing of the air and gas within the mixing chamber 17, before the gases reach the wire gauze 18, beyond which the flame is burning.

It is to be noted that the slots 16 and 23 80 are not only helical or spiral but also are set at an angle (partly tangential or non-radial) to the cone shaped or cylindrical member, which produces a much greater whirling motion of the gases in the chamber 17 than 85 would be the case if the holes or slots were made substantially radially (perpendicular to the surface of said cone-shaped member).

It is a well known fact that a candle, or 90 an oil lamp wick cannot be kept lighted, in many underground workings where the air is "bad"; yet not bad enough to cause great distress in breathing. In such a case we probably have at least 12 to 16% of O,—yet one cannot light a match or a candle, or in 95 fact, maintain combustion. It is not a far stretch of imagination, therefore, to picture an atmosphere in a closed furnace, which may possibly carry 2, 4, or 6% O but which would still refuse to support the combustion 100 of a combustible gas. Therefore, it becomes highly important to cause such a mixture of air (for combustion) and gas,—at the most desirable point,—that complete 105 consumption of the air will be accomplished, where desired. In both of these burners, the gas and air are first admitted into the preliminary mixing chamber which comprises the space between the outlet and of pipe 12, and the cone-shaped body 15 (or the 110 cylindrical body 21) which latter member has restricted openings 16, (or 23) into an

inclosing pipe 14 (or pipe-section 14^a) these openings being made diagonally, that is the slots are helical, and are non-radial, so as to give a whirling motion to the mixed gases. Since the total area of the openings 16 (or 23) is less than the combined cross-sectional areas of the pipe 12, and the annular space between the pipe 12 and the pipe 19 (or pipe section 19^a) the gases will be caused to travel at a higher rate of speed through these openings, thereby giving a high velocity to the gas and air emerging from these openings, into the supplemental mixing chamber 17, thereby producing a very complete mixing of the gas and air within said supplemental mixing chamber, before the gas and air reach the wire gauze 18. The final discharge of the mixed air and gas through the screen at the end of the outside pipe must be therefore a very thorough mixture of the two, thus bringing about a complete consumption of the air; or to put it possibly a little more accurately in a technical sense, thus bringing about as complete a combustion of the gas as the total amount of air furnished will admit of.

What I claim as my invention is:—

1. A burner comprising inlet pipes for air and gas; a preliminary mixing chamber; an element forming the end of said chamber, said element being provided with non-radial curved slits, said slits having a total area, equal to less than the sectional area of said chamber; a supplemental mixing chamber adjacent said member provided with slits; and a gauze closing the end of said supplemental mixing chamber.
2. A gas burner comprising inlet pipes for air and gas, one of said pipes being lo-

cated within the other; a preliminary mixing chamber receiving both the gas and air from said pipes; a hollow body supported at and forming the outer end of said chamber, said body being provided with helical, non-radial slits of less than the sectional area of said chamber; a supplemental mixing chamber adjacent said hollow body, and a gauze closing the end of said supplemental mixing chamber.

3. A gas burner comprising inlet pipes for air and gas, one of said pipes being located within the other; a preliminary mixing chamber, receiving both the gas and air from said pipes; a hollow body supported at and forming the outer end of said chamber, said body being provided with helical, non-radial, spiral slits of less than the sectional area of said chamber; a supplemental mixing chamber adjacent said hollow body, and a gauze closing the end of said supplemental mixing chamber.

4. In a gas burner, a hollow body for producing a mixing of the gas and air, said body being provided with non-radial helical slits, arranged at an angle oblique to the axis of said body, substantially as described.

5. In a gas burner, a hollow body for producing a mixing of the gas and air, said body being provided with non-radial helical, spiral slits, arranged at an angle oblique to the axis of said body, substantially as described.

In testimony whereof I affix my signature in presence of two witnesses.

HOWARD F. WIERUM.
